UNITED STATES PATENT OFFICE

2,011,103

FURNACE DAMPER

John W. Franz, St. Louis, Mo., assignor of one-half to Lawrence J. Rasse, Fairbury, Nebr.

Application March 16, 1934, Serial No. 715,849

1 Claim. (Cl. 126—293)

My invention has relation to improvements in furnace dampers and it consists in the novel features of construction more fully set forth in the specification and pointed out in the claim.

The invention is principally directed to a combination damper and check-valve located in the smoke pipe or flue leading to the fire-box of the furnace, and it has for its principal object the combining of the damper and check-valve in a single unit that is inserted in the smoke pipe. Another object of the invention is to arrange the damper and check-valve in cooperative relation so that on operating the check-valve the damper will be automatically opened or closed to a proportional degree with the closing or opening of the check. In other words, as the check-valve is opened the damper is closed, and as the check-valve is closed the damper is opened.

A further object of the invention is to provide a by-pass so that there will always be a passage-way for the escape of gases, irrespective of the position of the damper, and means are associated with the damper for keeping the by-pass free from soot accumulations. Other advantages inherent in the invention will be better apparent from a detailed description thereof in connection with the accompanying drawing, in which:

Figure 1 is a side view of an ordinary hot-air furnace showing my invention applied to the smoke pipe thereof; Fig. 2 is an enlarged side elevation of a section of the smoke pipe showing my improved combined check-valve and damper applied to the smoke pipe; Fig. 3 is a vertical cross-section taken on the line 3—3 of Fig. 2; Fig. 4 is a top plan of the combined check-valve and damper mounted in the smoke pipe, with parts, however, broken away to show other parts in section; Fig. 5 is a vertical longitudinal section taken on the line 5—5 of Fig. 3 with the check-valve closed and damper open; and Fig. 6 is a similar section of that shown in Fig. 5 except that the check-valve is open and the damper closed.

Referring to the drawing, F represents a conventional hot-air furnace equipped with the usual flue or smoke pipe P, to which is applied my combined check-valve and damper A. The combined check-valve and damper may be termed a valve mechanism as the check-valve 1 and the damper 2 are mounted in the housing 3 so as to form a unitary structure capable of being applied to the smoke pipe P by merely cutting an opening o of the proper size in the smoke pipe and securing the housing thereover. In the present instance, the housing is secured to the smoke pipe by a plurality of bolts 4 passed through each

of the side walls 5 of the housing adjacent to their lower edges and the portion of the smoke pipe along the margin of the opening o (as shown in Figs. 1 and 5). The housing 3 forms a box-like superstructure above the smoke pipe P having its top surface 6 arcuate toward the rear and inclining forwardly toward the front of the housing. The forwardly inclined portion 6' has a rectangular opening 7 formed in it, which opening is adapted to be closed by the upper rectangular component 8 of the check-valve 1 when desired. The check-valve 1 has sides or wings 8', 8" shaped according to sectors of a circle and is rotatably mounted on a hinge pin 9 located on the geometrical center of said sectors, said pin passing through the walls 5, 5 of the housing and having its ends slightly upset to prevent its dislocation. A flap valve 10 is rotatably mounted in the sides 5, 5 of housing 3 and the hinge pin 11, to which the flap valve is secured, passes through the sides 5, 5 of housing 3 on the center of the arc describing the arcuate rear portion 6" of the top surface 6 of said housing. The lower edge 10' of the flap valve 10 is semi-circular so as to fit snugly in the smoke pipe P while the upper edge 10" is straight and is approximately in the plane of the top surface of the smoke pipe when the damper 2 is in its vertical or closed position. Secured to the damper 10 (preferably by welding) is a rectangular frame 12 having the component 13, which forms its outer margin, lying in close proximity to the inner surface of the arcuate portion 6" of the housing 3. The hinge pin 11 has its ends 14 extended at right angles to the pin proper to form arms which will engage with cam elements 15, 15 formed on the wing 8', 8" for a purpose presently to appear. It will also be observed that on one of the sides 5 of housing 3 is a spring catch 16 slightly below the plane of the arms 14 when the damper 10 is in its horizontal or open position. There are also a pair of spaded bosses 17 having threaded openings 18 on one of the sides 5 for the purpose of receiving a stud 19 to limit the amount of closing movement of the damper 10. The positioning of the stud 19 in either of the bosses 17 constitutes a matter of permanent adjustment for the particular furnace to which my improved device may be applied.

The operation of the invention is as follows:

In order to give the furnace F its maximum draft the operator releases the chain C so as to permit the check-valve 1 to close by gravity. As the valve descends the cam elements 15 on the wings 8' bear downwardly on the arms 14 to raise the damper 10 which assumes a horizontal

position when the check-valve is fully closed as shown in the drawing. It will be observed that as the damper 10 is swung upwardly the component 13 of the frame 12 moves along an arcuate path in close proximity to the arcuate portion 6" of the housing 3. During this, any soot accumulations on the inner surface of the housing 3 are wiped or scraped from the surface. Obviously, when the check valve 1 is raised for the purpose of checking the draft, the damper 10 moves downwardly to assume a vertical position when the check valve is fully opened. During this movement of the damper the frame 12 is again rotated to remove soot accumulations. Thus every time the dampers are operated any accumulated soot will be removed from the arcuate portion of the housing 3. This prevents the building up of soot accumulations which, if allowed, would ultimately restrict the passage between the damper 10 (when closed) and the portion 6" of the housing. It is one of the objects of the invention to constantly maintain this passage for a by-pass so that even when the dampers are in position to fully check the draft through the smoke pipe P there will still be sufficient draft to carry products of combustion out of the furnace and through the flue.

It is well known that the amount of draft will vary for different furnace installations, depending on other factors, such as the character of the chimney, and in order to make suitable adjustment to compensate for such variations I have provided a stop pin or stud 19 which may be inserted in either of the threaded openings 18 to limit the closing movement of the damper 10. When the stop pin is in place one of the arms 14 will impinge on it and be arrested in its upward movement when the gate-valve 1 is raised, and even though the gate-valve may be raised to its

maximum position the damper 10 will not move further after the arm 14 engages the stop pin. I consider this a desirable feature as in some furnace installations there may not be sufficient draft to carry off the products of combustion if the damper 10 is allowed to swing entirely to closed position. 5

The purpose of the spring catch 16 is to serve as a detent for the damper so that it may be maintained in open position irrespective of the 10 position of the gate-valve if desired. It might be desirable to temporarily lock the damper in open position if the operator is removing ashes from the ash pit and the gate-valve is held in open position at some point removed from the furnace. 15

From the foregoing it is apparent that I have provided a combination check-valve and damper that is simple and certain in its operation, and due to its compact unitary structure may be easily applied to any furnace without any alterations beyond those which are necessary for the mere insertion of an ordinary check-valve. 20

Having described my invention, I claim:

A device of the character described comprising a housing, a check-valve, a damper mounted 25 in said housing, said check-valve and damper being cooperatively associated so that upon the operation of one the other will be automatically operated, and the damper having its upper end spaced from the wall of the housing containing 30 the check-valve to provide a by-pass adjacent to said check-valve when the damper is closed, and a scraper projecting from the damper to close proximity with the housing walls and movable so as to scrape the accumulations therefrom and maintain the space between the damper and said walls. 35

JOHN W. FRANZ.
